UNITED STATES PATENT OFFICE.

BERNARD LINCOFF, ISAAC SEFF, AND HENRY GÜNTHER, OF
NEW YORK, N. Y.

LIGHTING DEVICE FOR CIGARETTE-BOXES.

SPECIFICATION forming part of Letters Patent No. 364,595, dated June 7, 1887.

Application filed February 17, 1887. Serial No. 228,011. (No model.)

To all whom it may concern:

Be it known that we, BERNARD LINCOFF and ISAAC SEFF, both citizens of the United States, and HENRY GÜNTHER, a citizen of the 5 German Empire, all residing at New York, in the county and State of New York, have invented new and useful Improvements in Boxes for Cigarettes and Similar Articles, of which the following is a specification.

10 This invention relates to improvements in boxes for cigars, cigarettes, and other objects, as set forth in the following specification and claims, and illustrated in the accompanying drawings, in which—

15 Figure 1 is a perspective view of a box. Fig. 2 is a perspective view of a cover. Fig. 3 is a perspective view of a box and of a cover. Fig. 4 is a transverse section of a box and cover.

20 Similar letters indicate corresponding parts. In the drawings the letter A designates a box. B is a cover. To the box is secured one or more strips or supports, C, of cloth, paper, or other suitable flexible material. The strip

25 or support C is provided with tinder or combustible material D. The combustible or igniting material D is preferably placed on the strip or support C in sections, so that each section of combustible material can be ignited

30 and consumed independently of the other sections. One end of the strip C is secured to the box A, and the other end of the strip is left free.

35 The cover B is provided with a suitable friction-surface or igniting-surface, E. By bending the free end of the strip C, as seen in Fig. 3, and rubbing the combustible material D on the friction-surface E, the combustible material D will be ignited. A cigar or cigarette 40 can thus be lighted.

A convenient arrangement is to have the number of combustible sections D correspond to the number of cigars or cigarettes in the box A, so that each cigar or cigarette from 45 said box will have a lighter provided for such cigar or cigarette.

As the combustible sections D can be lighted

without detaching the strip or support C from the box by simply lapping the free end of the strip over the igniting-surface E, the strip C, 50 with its combustible material, will not be separated from the box A, and the strip will not be lost from the box.

In place of securing one end of the strip C, said strip C may be secured intermediate of 55 its ends, and the ends of the strip C be left free to engage the igniting-surface E.

The drawings show a box with a sliding cover. Such boxes are compact, durable, and easily handled.

60 A suitable combustible material can be obtained by mixing the following substances in the following proportions: chlorate of potassa, six parts; sulphuret of antimony, two to three parts; glue, one part. For the friction-surface mix amorphous phosphorus, ten parts; sulphuret of antimony or peroxide of manganese, eight parts; glue, three to six parts, and spread the last-named composition thinly upon the box or support, so as to form the 70 friction-surface E.

The strip C is advantageously made of asbestos, which, besides being flexible, is also non-combustible.

What we claim as new, and desire to secure 75 by Letters Patent, is—

1. The combination, with a box, A, of a strip or support, C, provided with igniting material D and secured at one of its ends to the box A, and a cover, B, provided with an 80 igniting or friction surface, E, substantially as set forth.

2. As a new article of manufacture, a box for cigars or cigarettes having secured to it one end of a strip, C, (one or more,) provided 85 with igniting material D, arranged in sections and having a cover, B, provided with an igniting or friction surface, E, substantially as set forth.

3. The combination, with a cover, B, having 90 an igniting or friction surface, E, of a box, A, and a strip, C, secured at one end to the box, said strip being provided with igniting material D, and the free end of the strip

C being adapted to engage the igniting or friction surface E, substantially as set forth.

4. The combination, with a cover, B, having an igniting or friction surface, E, of a box, A, and a strip, C, secured to the box, said strip being provided with igniting material D, and the strip C being adapted to engage the igniting or friction surface E, substantially as set forth.

In testimony whereof we have hereunto set to our hands and seals in the presence of two subscribing witnesses.
